(57) **CLAIM**

The ornamental design for a traction limiter handle, as shown and described.

DESCRIPTION

FIG. 1 is a perspective view of a traction limiter handle showing our design.

FIG. 2 is a front view thereof.

FIG. 3 is a rear view thereof.

FIG. 4 is a side view thereof.

FIG. 5 is another side view thereof.

FIG. 6 is a top view thereof; and,

FIG. 7 is a bottom view thereof.

The broken lines shown the circle details in FIG. 7 indicate the boundary of the claimed design; the broken lines form no part of the claimed design.
